ADJUSTABLE BROILER GRID

Joseph E. Leonard, Berkeley, Calif., assignor to
Hammer-Bray Company, Ltd., Oakland, Calif.,
a corporation of Nevada

Original No. 2,135,309, dated November 1, 1938,
Serial No. 16,397, April 15, 1935. Application
for reissue August 16, 1939, Serial No. 290,520

9 Claims. (Cl. 126—41)

The invention relates to a means arranged for use in a broiler compartment of a range or stove for moving the broiler grid or pan to, and holding same in, different elevations in the compartment.

5 An object of the invention is to provide a means of the character described, which will be formed as a part of a drawer which is movable into and out of the broiler compartment and upon 10 which the broiler grid or pan is carried.

Another object of the invention is to provide 15 a means of the character described which requires no mutilation of or attachment to any of the stove members, yet is easily and conveniently operated by means which remains concealed except when the broiler compartment is opened.

A further object of the invention is to provide 20 a means of the character described, in which the operative mechanism thereof is at all times concealed from view and fully shielded from the heat and cooking products in the compartment.

A still further object of the invention is to so 25 design the device that when the grid and pan are removed from the broiler compartment, the portion of the device remaining in the compartment will be unobtrusive, easy to clean, and permit of the free use of practically the entire 30 space in the compartment.

The invention possesses other objects and features of advantage, some of which, with the foregoing, will be set forth in the following description of the preferred form of the invention which is illustrated in the drawing accompanying and forming part of the specification. It is to be 35 understood, however, that variations in the showing made by the said drawing and description may be adopted within the scope of the invention as set forth in the claims.

Referring to said drawing:

40 Figure 1 is a horizontal sectional view taken through a stove broiler compartment equipped with the grid adjusting means of my invention.

Figure 2 is a sectional view taken at right angles to the view shown in Figure 1, the plane 45 of the section being indicated by the line 2—2 in the latter figure.

Figure 3 is a vertical sectional view taken at right angles to Figure 2, the plane of the section being indicated by the line 3—3 of Figure 2.

50 Figure 4 is a detail vertical sectional view of a portion of the lever retaining rack used in the device.

In the embodiment of the invention here described, the means is designed for use in connection with a roller supported carrier 2 upon

which the broiler pan 3 or other grid element is removably mounted for positioning in or out of the broiler compartment 4. The latter comprises a part of a stove or range and has disposed therein, but not herein shown, a burner or the like which is usually positioned in fixed relation near the top of the compartment.

The carrier 2, as here illustrated, includes a drawer-like structure 6 formed with a bottom wall 7, side walls 8, and a rear wall 9, the front 10 of the drawer structure being preferably left entirely open so that the pan may be moved into or out of the structure and access readily had to the pan if desired without removing the same from the compartment. Support of the carrier 15 is by means of rollers 11 carried by the former and engaging guides or tracks 12 on the bottom of the compartment, and rollers 13 mounted on the tracks and engaged by strips 14 on the under side of the drawer structure 6.

20 Positioned within the structure 6 and preferably located adjacent the side walls 8, are a pair of movable rests 16 on which the pan 3 is arranged to be supported while on the carrier. The rests extend parallel to said walls, that is 25 from the front to the rear of the structure, and are preferably in the form of strips or plates which may be caused to lie practically flat upon the bottom wall 7. Desirably the portions of the wall 7 underlying the rests 16 are depressed so 30 that when the latter are caused to lie in the position aforesaid the rests will be coplanar with the portion 17 of the wall 7 therebetween, and form therewith a relatively smooth flat bottom 35 on which the pan may be superimposed.

35 As will be clear from Figure 3, the pan is arranged to be supported on the beaded edges 18 of the rests, and the rests are so mounted that such edges may be raised or lowered to thereby move the pan when disposed thereon, to different 40 elevations on the carrier. The feature of having the drawer entirely open at the front in combination with the feature of having the grid rests extending lengthwise of the drawer, makes practical and safe in all positions of the rests, 45 the sliding insertion or withdrawal of the pan into or from the drawer from the front thereof. To afford the desired raising or lowering of the edges 18, the rests are pivotally connected to the drawer structure for movement about a horizontal axis parallel to the side walls, and as here shown such connection is made for each rest by means of a rod 19 fixed for movement with the associated rest and pivotally mounted at one end in the rear wall 9 and at the other end in an 50 55

ear 21 formed on a frontal member 22 at the open end of the structure. The member 22 is secured to the bottom and side walls and incidentally provides a reinforcement for the structure. Each 6 of the rods 19 is located immediately adjacent the side walls but above the depressed portion of the bottom wall, and desirably the portion of the rest at the rod is offset upwardly and formed to completely cover the rod. In the latter connection it will be noted that the offset occurs 10 at the edge of the rest adjoining the side walls and since in the usual pan design the body portion is narrower than the top or flanged portion, the offsets will in no way interfere with the proper 15 positioning of the pan upon the bottom wall of rests in any position of the latter.

To rotate the rests about their pivot axes, there is here shown provided a lever 23 conveniently fulcrumed to the bottom wall by a bolt 24 and 20 connected by means of links 26 to crank arms 27 fixed to the rods, the links for the different rods as will be clear from Figure 1, being connected to the lever at opposite sides of the fulcrum bolt. The lever and links are all located on the under 25 side of the bottom wall, while the arms extend from the links to the rods through slots 28 in such wall. Access to the lever so as to rotate the rests is afforded at the front of the structure where a portion of the lever extends through an 30 arcuate slot 29 formed in the frame member 22. Desirably the exposed end of the lever is provided with a handle or knob 31 to facilitate operation thereof by the user.

Means are provided in association with the 35 lever for releasably locking same in any one of a selective number of positions so as to thereby cause the rests and consequently the pan to be maintained at the desired elevation. As here shown, such means comprises a segmental rack 32 40 conveniently fixed to the frontal member on the under side thereof and having a series of spaced stops 33 lying in the horizontal path of movement of the lever. The lever is permitted a limited vertical movement and the stops 33 are 45 so positioned that the lever will clear same when the lever is moved horizontally while in raised position. On the other hand, when the lever is released it will drop into position for engagement with the stops so that its horizontal movement 50 will be limited. Preferably the faces of the stops, are inclined as shown in Figure 4 that due to the weight of the pan, the latter tends to move and hold the lever in locked engagement with the stops, and yet at the same time when the lever is 55 moved to elevate the pan, the former will readily slide over the stops.

If desired, the member 22 may be marked to correspond with the stops in order that the 60 operator may readily place the lever in a position required for placing the pan at a desired elevation on the carrier.

It will now be clear that practically all of the 65 parts for effecting movement of the broiler grid and for maintaining same in desired position are, with the exception of the rests, disposed below the bottom of the drawer, are completely shielded from the interior of the compartment thereabove and particularly so when the rests are in their lowermost position and covering the slots 28. Furthermore, since the rests may be positioned 70 to lie flat upon the bottom of the drawer, and in such position form a smooth and practically uninterrupted portion of such bottom, the task of cleaning the drawer is rendered simple and easy 75 and at the same time no obstructions will be en-

countered by the pan when being moved into or out of the drawer. A grill 36 or the like may be placed in or upon the pan, and it will be understood that the term grid or pan, as herein used, is intended to cover any element upon which the article to be broiled is supported. By reason of the fact that the grid rests remain spaced and leave the central portion of the bottom of the drawer unobstructed in all positions of the rests, ready access to the pan or the like 10 from the front of the drawer for gripping the same is considerably facilitated.

I claim:

1. In an adjustable grid for a broiler, a supporting unit arranged for positioning in said 15 broiler and having a portion defining a horizontal partition for the broiler compartment, sectional wall portions providing a grid-rest at the side of said partition and mounted for pivotal movement from a position coplanar to said partition 20 to a position elevated therefrom, mechanism positioned substantially exclusively on the under side of said partition and manually operable from the front of the unit to effect pivotal movement of the rests, and means to hold the rests selectively 25 in different positions.

2. In an adjustable grid for a broiler, a supporting unit arranged for positioning in said 30 broiler and having a portion defining a horizontal partition for the broiler compartment, grid-rests 35 on the upper side of said partition pivoted to said unit for movement about horizontal axes at the side edges of said partition for movement to and from a position substantially coplanar with said partition, a pan arranged for positioning on said 40 rests to engage an edge thereof, crank arms fixed to said rests for pivotal movement therewith and extending through slots in said partition, a lever carried by said unit and pivotally mounted on the under side of said partition and having one arm 45 extended to the front of said unit, links connecting said lever and crank arms whereby on rocking of said lever said rests will be moved about their pivots to raise and lower said pan, and means for releasably locking said lever in 50 different positions.

3. In an adjustable grid for a broiler, a drawer mounted for movement into and out of said 55 broiler and having a portion defining a horizontal partition for the broiler compartment when the drawer is disposed therein, grid rests positioned on the upper side of said partition and mounted to swing about horizontal axes along the side edges of said partition for movement upwardly 60 from and downwardly to a position substantially coplanar with said partition, a frame member extending across the front portion of said drawer and providing a substantial extension of said 65 partition, said partition and said member having slots therein, mechanism carried by said unit for swinging said rests about their pivotal axes and including parts extending through the slots in said partition and connected to said rests, and a lever operatively connected with said parts and extending through the slot in said frame member to an exposed position at the front of said unit and being urged in one direction by the supported weight on said rests, and a plurality 70 of stops selectively engageable by said lever for holding the latter against movement in said direction and to hold said rests in different positions and being of such form that the force of the lever thereagainst will hold the lever in locking engagement therewith.

4. In an adjustable grid for a broiler, a supporting unit arranged for positioning in said broiler and including a relatively fixed wall portion spaced inwardly from the sides of said unit, 5 movable grid supporting wall portions located at the sides of said first portion and extending substantially coplanar and forming therewith in one position a horizontal partition substantially completely across the unit, and means operable from 10 the front of the unit and positioned under said fixed portion for elevating said movable portions to raise the grid supported thereon.
5. In an adjustable grid for a broiler a supporting unit arranged for positioning in said 15 broiler and including a relatively fixed horizontal wall section spaced inwardly from the sides of said unit, movable wall sections forming in one position substantially horizontal extensions of said first section, a grid having a central depressed portion resting on said movable sections and having raised side portions overlying and spaced from said movable sections, said movable sections being pivoted at points between said raised side portions and said fixed section and 20 adjacent the sides of said unit, and means covered by said fixed and movable sections operative from the front of the unit for moving said sections about the pivots.
6. In an adjustable grid for a broiler, a supporting unit slidable horizontally into and out of the broiler compartment and having a portion defining a horizontal partition therefore having a substantially unobstructed front and separate members providing grid rests extending substantially parallel to the direction of movement of 30 said partition and mounted for pivotal movement from a position substantially coplanar to said partition to a position elevated therefrom, and mechanism positioned substantially exclusively on the under side of said partition and 35 manually operative from the front of the unit to effect pivotal movement of the rests.
7. In an adjustable grid for a broiler, a supporting unit arranged to slide horizontally into and out of the broiler compartment through the 40 front thereof and having a portion defining a horizontal partition for the compartment and having a substantially unobstructed front, separate members providing grid supporting rails 45 mounted on said supporting unit for pivotal 50 movement from a position substantially coplanar with said partition to a position elevated therefrom and arranged to extend fore and aft of said unit in all of the positions of the members whereby the grid may be supported by both rails at all elevations and in all positions of the grid during movement upon said rails fore and aft of the unit, and mechanism positioned substantially exclusively on the under side of said partition and manually operative from the front of the unit to effect pivotal movement of the members. 5
8. In an adjustable support for a broiler grid, a substantially open-front drawer having a horizontal bottom wall and a horizontal frame piece 15 extending across the front edge of said bottom wall and having its upper surface slightly above the upper surface of the wall, separate members extending lengthwise of said drawer and pivotally connected to said frame piece and a rear portion of said drawer and having grid rest portions extending substantially from said frame piece to the rear end of said drawer and actuated upon pivotal movement of the members to move to or from a position on said wall with the upper surface thereof extending to a point lower than but substantially adjacent to said upper surface of said frame piece, and means operable from the front of the drawer to move and hold said members in different positions, said members being so arranged in said drawer as to leave the central portion of said wall free and uncovered in all of the positions of the members. 20
9. In an adjustable support for a broiler grid, a drawer having a horizontal bottom wall, separate independent members providing grid rests extending lengthwise of and over said drawer and pivotally mounted thereon for movement from a position substantially coplanar to said wall to a position elevated therefrom, said members being arranged to remain spaced horizontally from each other so as to leave unobstructed the space over said bottom wall between said grid rests in all of the elevated positions thereof, means carried under said wall for moving said members, and means at the front of said drawer for operating said moving means and having the uppermost portion thereof extending to adjacent but lower than said rests in their lowermost position. 30

JOSEPH E. LEONARD.
